UNITED STATES PATENT OFFICE

169,684

MAGNETIC DRUM UNIT

George H. Kress, Endwell, N. Y., and Carl W. Sundberg, Detroit, Mich., assignors to International Business Machines Corporation, New York, N. Y., a corporation of New York

Application December 18, 1952, Serial No. 22,760

Term of patent 14 years

(Cl. D26—5)

To all whom it may concern:

Be it known that we, George H. Kress and Carl W. Sundberg, citizens of the United States of America, residing respectively at Endwell, county of Broome, State of New York, and Detroit, county of Wayne, State of Michigan, have invented a new, original, and ornamental Design for a Magnetic Drum Unit, of which the following is a specification, reference being had to the accompanying drawings forming part thereof.

Fig. 1 is a perspective view of a magnetic drum unit, embodying our design.

Fig. 2 is a rear elevation of the same.

Fig. 3 is a side elevation of the same as seen from the left end.

We claim:

The ornamental design for a magnetic drum unit, as shown.

GEORGE H. KRESS.
CARL W. SUNDBERG.
